UNITED STATES PATENT OFFICE.

LUTHER C. MCNEAL, OF ROCHESTER, NEW YORK.

DIAPHRAGM-PUMP.

985,917.

Specification of Letters Patent.

Patented Mar. 7, 1911.

Application filed June 27, 1910. Serial No. 569,691.

To all whom it may concern:

Be it known that I, LUTHER C. MCNEAL, a citizen of the United States, and resident of Rochester, in the county of Monroe and 5 State of New York, have invented certain new and useful Improvements in Diaphragm-Pumps, of which the following is a specification.

This invention relates to pumps of the 10 type in which a flexible diaphragm is employed in place of a piston.

The object of the invention, generally stated, is to produce a pump of this kind which shall be simple in construction and efficient in operation. To these ends my improved diaphragm-pump is so constructed that oscillating movements are substituted for reciprocating or sliding movements in the mechanism by which the diaphragm is 20 actuated. A pump so constructed is particularly adapted for use as an air-pump, and further novel features of the invention reside in the form of the pump-casing, by means of which it is adapted to coöperate with the 25 novel form of diaphragm, the means for producing a fluid-tight joint at the pivotal supporting-point of the diaphragm-mechanism, and the novel form of valve by which the 30 inlet and outlet-passages of the pump-casing are controlled.

In the accompanying drawings: Figure 1 is a longitudinal vertical section on the line 1—1 in Fig. 2, of a pneumatic cleaning-device embodying a pump constructed in accordance with the present invention; Fig. 2 is a section on the line 2—2 in Fig. 1, looking from left to right in said figure; Fig. 3 is an enlarged detail view of two of the air-valves employed in connection with the 40 pump; and Fig. 4 is a section on the line 4—4 in Fig. 3, looking upward in said figure.

The illustrated embodiment of my invention comprise a diaphragm having a flexible 45 marginal portion and a comparatively rigid middle portion, the latter being pivotally mounted so as to oscillate from side to side of the general plane of the diaphragm. The flexible marginal portion comprises a sheet 50 5 of leather, or other suitable material, while the rigid portion comprises a plate 6, preferably of metal, which is pivoted upon a horizontal axis by means of trunnions 7 projecting from the lateral edges of the plate 55 6. A socket 8 extends from the upper edge of the plate and is adapted to receive a

handle 9 which may be of any convenient length. The rigid portion of the diaphragm comprises also two thin metal plates 10 and 11 which are clamped on either side of the 60 plate 6 by means of screw-bolts 12, and these plates serve as means for securing the rigid and flexible portions of the diaphragm together, as the middle portion of the leather 5 is clamped between the plates 10 and 6, 65 as shown in Fig. 1.

The diaphragm above described is mounted within a casing which comprises a body-portion 13 and an end-portion 14. These two portions of the casing are joined, in 70 the plane of the diaphragm, by means of flanges 15 on the respective parts secured together by screw-bolts 16. The edges of the leather 5 are interposed between the flanges 15, and in this manner the diaphragm is held securely in place and is caused to divide the casing into two pump-chambers.

To prevent the escape of air from the pump-chambers at the pivotal support of 80 the rigid diaphragm-member the upper margin 17 of the sheet 5 extends beyond the plate 10 and is bent outwardly upon the top of the casing, as shown in Fig. 1. A metal plate 18 is clamped down upon the margin 85 17 by means of screws 19, and in this way is prevented the escape of air at this point from the space between the diaphragm and the end-portion 14 of the casing. To perform the corresponding function for the 90 other pump-chamber a second sheet 20 of flexible material is clamped between the plate 6 and the plate 11, and the sheet 20 has its upper margin 21 clamped against the upper surface of the casing by means 95 of the plate 18, which extends entirely around the plate 6 for this purpose.

The trunnions 7 of the diaphragm are journaled in bearing-blocks 23 which are mounted upon the clamping-plate 18. This 100 plate carries also two buffers 24 of rubber, or other resilient material, which are engaged by lugs 25 on opposite sides of the plate 6 to limit the oscillating movement of the diaphragm.

The end portion 14 of the casing is inclined downwardly and outwardly so as to conform roughly to the position occupied by the diaphragm in its extreme left-hand position, and the body-portion of the casing 110 is provided with a partition 26 which occupies a similar relation with the diaphragm

when the latter is in its extreme right-hand position. In this manner pump-chambers are produced in which the clearance-space is limited, as is desirable to secure positive 5 action in the pump. To further limit the clearance-space the lower corners of the pump-chambers are partly filled by sheet-metal boxes 27 and 28 which have the further function of valve-chambers for the 10 valves by which the flow of air through the pump is controlled.

The valve-chamber 27 (Fig. 1) is divided by a vertical partition 29, and the valve-chamber 28 is similarly divided by a partition 30. The valve-chamber 27 is provided, at one side of the partition 29, with an inlet-valve 31, and at the other side with an outlet-valve 32, and the valve-chamber 28 is provided with corresponding valves 33 and 34. Air is admitted from the right-hand side of the partition 26 in the pump-casing through an opening 35, and is then drawn through the valve-chamber 28 and through the inlet-valve 33 into the right-hand pump-chamber, this action being produced by the left-hand movement of the diaphragm to the position shown in Fig. 1. At the same time air is expelled from the left-hand pump chamber through the outlet-valve 32, and 30 the air so expelled escapes from the valve-chamber 28 through a suitable opening (not shown) in the bottom of the casing. Upon the movement of the diaphragm in the opposite direction air is drawn into the left-hand pump-chamber through the inlet-valve 31, this air being supplied to the valve-chamber 27 through a tube 37 connecting the valve-chamber with the body of the casing 13, as shown in Fig. 1. At the same 40 time air is expelled from the right-hand pump-chamber through the outlet-valve 34 and escapes from the valve-chamber 28 through an opening in the bottom of the casing provided with a wire-gauze screen 45 36 (Fig. 2).

The novel form and construction of the valves hereinbefore referred to is illustrated particularly in Figs. 3 and 4. Each valve comprises a piece 38 of leather, or other suitable flexible material, which is mounted upon the inclined front wall of the valve-chamber 27 or 28 adjacent to two openings 39 in the wall which constitute the inlet or outlet openings, as the case may be. The flexible material 38 is secured only at its middle portion, by means of studs 40 fixed in the wall, so that the ends of the flexible material are free to move toward and from the surface of the partition and thus to act as flap-valves to 50 control the two openings, respectively. In addition to the flexible portion each valve comprises two substantially-rigid metal plates 41 and 42 which are pivoted upon the studs 40 so as to have a limited pivotal 55 movement with the flexible portion 38.

Each of these plates is provided with an upwardly-extending arm 43, and a rod 44 passes loosely through openings in the two arms, being secured therein by heads at its ends. Upon the rod 44 is a compression-spring 45 which engages the arms 43 at its 70 respective ends.

The valve construction above described is such that both ends of the flexible valve-member 38 are held to their seats with substantially-equal pressure, owing to the fact that the action of the spring 45 on the plates 41 and 42 is necessarily equal, whatever the position of the valve may be. This arrangement has the further advantage that the 80 valve may be quickly and conveniently removed from its position when necessary for cleaning or repair. To this end the openings 48 which engage the studs 40 are made of key-hole form, so that by slightly compressing the spring 45 and moving the plates 41 and 42 toward each other the large ends of the openings may be brought beneath the heads of the studs 40, and the plates may then be at once removed from the studs, thus 90 permitting convenient access to, or removal of, the flexible part 38 of the valve.

The inclined position of the front walls of the valve-chambers 27 and 28, in addition to restricting the clearance-space in the 95 pump-chambers as above described, has the further advantage that it tends to maintain the valves free from any particles of dust or dirt which might otherwise remain upon the valves or the valve-seats and which 100 would interfere with their operation.

In the drawings the pump hereinafter described is shown as used in connection with a vacuum-cleaning device, as it is particularly adapted for such use. In this connection the casing 13 is provided with a dust-bag 46 to which dust-laden air is supplied through an inlet 47. The air is drawn through the dust-bag into the casing and thence through the pump in the manner above described. It will be understood that the invention is not limited to employment 105 in connection with a vacuum-cleaning device, but that the novel pump may be employed in various connections and for pumping 110 various fluids.

By the peculiar form and construction of the diaphragm and the pivotal mounting of its rigid portion the mechanism of the pump is simplified, since a single rigid mechanical 120 element or member, comprising both the rigid portion of the diaphragm and the lever by which it is actuated, constitutes the entire mechanism of the diaphragm, and in this manner also the friction of the mechanism is greatly reduced, since sliding joints are entirely eliminated. The flexible marginal portion of the diaphragm is made sufficiently loose, as shown in Fig. 1, to permit a substantial movement of the dia- 125 phragm 130

phragm to either side of its median position, and the construction as a whole is such that the diaphragm may move equal distances in opposite directions so as to operate effectively as a double-acting pump. It will be obvious, however, that the same diaphragm may be employed as an element of a single-acting pump where such an arrangement may be preferable.

10 I claim:—

1. A diaphragm-pump having, in combination, a casing, and a diaphragm comprising a loose, flexible, marginal portion secured at its edges to the casing, and a comparatively rigid middle portion pivoted upon the casing substantially in the plane of the diaphragm and free to oscillate to opposite sides of said plane.

2. A diaphragm-pump having, in combination, a casing, a diaphragm comprising a loose, flexible, marginal portion secured at its edges to the casing, and a comparatively rigid middle portion pivoted upon the casing substantially in the plane of the diaphragm, and a flexible fluid-tight connection between the casing and the diaphragm adjacent to the pivotal support of the latter.

3. A diaphragm-pump having, in combination, a casing, and a diaphragm located in the casing and dividing the latter into two pump-chambers, the diaphragm comprising a loose, flexible, marginal portion secured at its edges to the casing, and a comparatively rigid middle portion pivoted adjacent to one wall of the casing and substantially in the plane of the diaphragm, said

rigid portion being free to oscillate to opposite sides of said plane.

4. A diaphragm-pump having, in combination, a casing, and a diaphragm comprising a sheet of flexible material secured to the casing substantially throughout its marginal portion, a comparatively rigid middle portion pivoted upon the casing substantially in the plane of the diaphragm, and a second sheet of flexible material connecting said rigid portion with the casing adjacent to the pivotal axis of the diaphragm.

5. A diaphragm-pump having, in combination, a diaphragm, a casing provided with two openings, and a valve controlling said openings and comprising two pivotal members adapted to close the openings, respectively, and a single spring connected at its ends with said members respectively so as to have equal action thereon.

6. A diaphragm-pump having, in combination, a diaphragm, a casing provided with two openings, and a valve controlling said openings, said valve comprising two plates provided with openings at their adjacent edges, studs upon which said plates are pivotally mounted, and a single spring connected at its ends with said plates, respectively, and operating both to hold the valve in closed position and to maintain the plates in engagement with said studs.
